UNITED STATES PATENT OFFICE.

JOHN P. ASHEY, OF WORCESTER, MASSACHUSETTS.

APPARATUS FOR OPERATING ALARMS.

1,129,057.

Specification of Letters Patent. Patented Feb. 23, 1915.

Application filed January 5, 1912. Serial No. 669,692.

To all whom it may concern:

Be it known that I, JOHN P. ASHEY, a citizen of the United States, residing at Worcester, in the county of Worcester and Commonwealth of Massachusetts, have invented a new and useful Improvement in Apparatus for Operating Alarms, of which the following is a specification, accompanied by drawings forming a part of the same.

10 My invention relates to an alarm operating mechanism and particularly to that class which is used in connection with automatic sprinkler systems.

15 It has for its object to simplify the construction of this class of devices and render their action more efficient and certain. I accomplish this object by the construction and arrangement of parts as hereinafter described and pointed out in the annexed claims.

20 Referring to the accompanying drawings, Figure 1 represents a central vertical sectional view through the valve casing and receiving chamber of an apparatus for operating an alarm and embodying my invention, showing the check valve in its closed position. Fig. 2 is a similar sectional view, showing the check valve in a raised position. Fig. 3 is a plan view shown in section on 25 the plane of the broken line 3-3, Fig. 1 with a portion of the check valve removed.

Similar reference characters refer to similar parts in the different figures.

An automatic alarm device is employed 35 in connection with a sprinkler system for the purpose of causing an alarm to be sounded whenever a current of water under pressure is caused to pass continuously through the system as would be caused by the opening of one or more sprinkler heads, and the apparatus for controlling the alarm in connection with a sprinkler system must be so constructed that a temporary flow of water through the supply pipe, such as might be 40 caused by a water hammer, will not cause an alarm to be sounded.

In the accompanying drawings I have shown so much of a device for controlling an alarm by the flow of water through the 45 supply pipe as will illustrate the character of my present invention as applied to an automatic sprinkler system.

My present invention is designed to be operative in connection with the usual check valve comprised in an automatic sprinkler system. The check valve of the sprinkler

system is shown at 1 and the valve seat at 2, by which the check valve is arranged to close the water supply passage 3 and prevent the flow of water under pressure into a valve chamber 4 and from the valve chamber through a passage 5 to the sprinkler heads. In the present instance the check valve 1 is attached to a lever 6 upon a pin 7 held in a valve casing 8. The valve seat 2 is provided with an annular channel 9 which is normally closed by the check valve 1. Upon one side of the valve seat 2 the annular channel 9 connects with a passage 10 leading to a receiving chamber 11. The receiving chamber 11 communicates with a pipe 12, which is closed by a diaphragm 13 upon which a metal post 14 is mounted adapted, as the diaphragm is raised, to be moved between metal bars 15 and 16 forming the terminals of an electric circuit. The diaphragm is pressed downward by a spring 17, holding the post 14 normally out of contact with the bars 15 and 16.

The lower end of the receiving chamber 11 is provided with an outlet pipe 18. The passage through the pipe 18 is provided with a valve 19 adapted to close the passage through the pipe 18 by its contact with a valve seat 20. The valve 19 is carried on 35 the end of a pivoted lever 21, pivoted at 22 upon the lower end of a plate 23 attached to one of the side walls of the chamber 11. The lever 21 is curved upwardly at 24 and extends through the passage 10, with its upper end 25 extending above the valve seat 2 when the check valve 1 is raised as shown in Fig. 2, allowing the weight of the valve 19 to carry it into contact with the valve seat 20 and close the outlet passage through the pipe 18. When the check valve 1 is closed, its weight is sufficient to depress the end 25 of the lever 21 and raise the valve 19 into the position shown in Fig. 1, thereby opening the outlet passage.

The casing 8 of the valve chamber 4 and the casing 27 of the receiving chamber 11 are preferably cast in a single integral piece having a common dividing wall 28, provided at its lower edge with an opening 29 with which the passage 10 in the valve seat communicates. The lever 6 upon which the check valve 1 is carried is provided with a spur 30 adapted, as the check valve is raised, to contact with a boss 31 on the inside of a removable cap 32.

The operation of my device is as fol-

lows:—The check valve 1 is normally closed in the position shown in Fig. 1. When a water hammer occurs, it is temporarily lifted a slight distance, as shown in Fig. 2. 5 When raised as shown in Fig. 2, the valve 19 is allowed to drop by its own weight and close the outlet passage through the pipe 18. When the flow of water caused by the water hammer ceases, the check valve falls into its 10 normal position, striking the end 25 of the pivoted lever 21 and lifting the valve 19, thereby opening the outlet passage and allowing the accumulated water in the receiving chamber 11 to escape. The receiving 15 chamber 11 is of such size that the accumulation of water due to water hammers is not sufficient to exert a pressure upon the diaphragm 13 great enough to overcome the tension of the spring 17. In case a 20 sprinkler head is opened, a flow of water through the system occurs which raises the check valve 1 into the position indicated by broken lines 33, Fig. 2. Water then flows into the receiving chamber 11 until the latter gradually 25 fills sufficiently to raise the diaphragm 13, thereby lifting the metal post 14 into contact with the bars 15 and 16 and completing an electric circuit, which includes a bell, not shown, by which an alarm is sounded. 30 The removable cap 32 allows access to the valve chamber 4, and a similar removable cap 34 permits access to the receiving chamber 11.

I claim,

- 35 1. In a mechanism for operating an alarm, a water supply passage having therein a valve chamber, a check valve within said valve chamber for normally closing said water supply passage, a receiving chamber, 40 a passage between said receiving chamber and said valve chamber normally closed by said check valve, an outlet for said receiving chamber, a valve for closing said outlet, and means for normally holding said outlet 45 valve open by the weight of said check valve when the latter is closed.
2. In a mechanism for operating an alarm, a water supply passage having therein a valve chamber, a receiving chamber, a

passage between said receiving chamber and 50 said valve chamber, a check valve within said valve chamber for normally closing said water supply passage and said passage between the receiving chamber and the valve chamber, an outlet for said receiving chamber, a valve for closing said outlet, and means for normally holding said outlet valve open by the weight of said check valve. 55

3. In a mechanism for operating an 60 alarm, a water supply passage having therein a valve chamber, a check valve within said valve chamber for normally closing said water supply passage, a receiving chamber having a normally open outlet, a passage between said valve chamber and said receiving chamber, a valve for said outlet, and means inclosed in said communicating passage operable by the movement of said check valve for opening and closing said outlet valve. 70

4. In a mechanism for operating an 75 alarm, a water supply passage, a valve and valve seat for closing said passage, a receiving chamber, a passage communicating at one end with the receiving chamber and terminating at its other end in the surface of said valve seat so as to be opened and closed by said valve, and means extending through said passage for controlling the accumulation of water in said receiving chamber. 80

5. In a mechanism of the class described, means for conveying a pressure medium, a normally closed check valve within said means, adapted to be opened by the passage 85 of pressure medium therethrough, a chamber provided with pressure actuated mechanism for operating an alarm, a passage between said chamber and said pressure medium conveying means normally closed by 90 said check valve, and means, operated by the weight of said check valve when in closed position for permitting the escape of pressure medium from said chamber.

JOHN P. ASHEY.
